UNITED STATES PATENT OFFICE

142,571

DESIGN FOR A BILL CLIP OR SIMILAR ARTICLE

Henry L. Lambert, New York, N. Y., and William Cole, Ridgefield Park, N. J.

Application June 23, 1945, Serial No. 120,286

Term of patent 7 years

(Cl. D74—2)

To all whom it may concern:

Be it known that we, Henry L. Lambert and William Cole, both citizens of the United States of America and residents respectively of New York city, State of New York, and Ridgefield Park, State of New Jersey, have invented a new, original, and ornamental Design for a Bill Clip or Similar Article, of which the following is a specification, reference being had to the accompanying drawing, forming a part hereof, in which:

Figure 1 is a top plan view of a bill clip or similar article, showing our new design; Fig. 2 is a side elevational view thereof; and Fig. 3 is a bottom plan view thereof.

We claim:

The ornamental design for a bill clip or similar article, as shown.

HENRY L. LAMBERT.
WILLIAM COLE.
